UNITED STATES PATENT OFFICE.

AMBROSE DIEFFENBACH, OF DEVIL'S LAKE, DAKOTA TERRITORY.

GRAIN-ELEVATOR.

SPECIFICATION forming part of Letters Patent No. 394,560, dated December 18, 1888.

Application filed June 2, 1888. Serial No. 275,825. (No model.)

To all whom it may concern:

Be it known that I, AMBROSE DIEFFENBACH, a citizen of the United States, residing at Devil's Lake, in the county of Ramsey and 5 Territory of Dakota, have invented a new and useful Improvement in Grain-Elevators, of which the following is a specification.

My invention relates to an improvement in grain-elevators adapted to be used in connection with fanning-mills; and it consists in the peculiar construction and combination of devices that will be more fully set forth herein-after, and particularly pointed out in the claim.

15 In the drawings, Figure 1 is a perspective view of my grain-elevator, showing the same attached to a fanning-mill. Fig. 2 is a vertical longitudinal sectional view of my improved grain-elevator. Fig. 3 is a top plan 20 view of the same.

A represents the case of the mill, which is of the usual construction, and B represents the semi-cylindrical fan-case, which is arranged on one end of the frame A in the usual manner.

25 C represents the frame of the elevator, which comprises a pair of side beams or boards, D, and a pair of cross-bars, E, which connect said beams or boards near the ends thereof. Journaled between the lower ends of the said 30 beams or boards is a roller, F; and G represents a similar roller, which is journaled between the upper ends of said boards or beams. The spindle at one end of said roller G is extended beyond one side of the elevator-frame, 35 and to the said spindle is rigidly secured a pulley, H.

I represents an endless elevator-belt, which passes over the rollers F G, and is provided with a series of cross cleats or flights, K, each 40 of which is made of a single piece of angle-iron, having one side secured to the outer side of the endless belt or apron and the other side projecting at right angles from said apron. The said cleats or flights are secured at a 45 suitable distance apart.

To the outer end of the elevator-frame is secured a trough or spout, L, which is of the

form here shown, is stamped or bent from a single piece of sheet or plate metal, and has a hopper, M, at its lower end, to which hopper the 50 mouth of a bag or sack is adapted to be attached. A pair of supporting-legs, M', have their upper ends pivoted to the outer end of the elevator-frame, and are thereby adapted to be folded against the sides of the frame 55 when not in use.

The elevator-frame has its lower end secured to the frame A at a point below the fan-case by means of metallic straps N, and said elevator-frame is also secured to the fan-case by 60 means of similar metallic straps, O, the elevator-frame being supported in an inclined position by the legs M'.

P represents an endless belt, which connects the pulley H with a pulley on the end 65 of the fan-shaft, whereby the rotation of the said fan will be communicated to the upper roller, G, and thereby cause the endless belt or elevator to move in the direction indicated by the arrows in Fig. 2, and consequently 70 carry the grain which is discharged from the fanning-mill to the sack or bag.

Having thus described my invention, I claim—

The combination of the frame D, the rollers F G at the inner and outer ends thereof, the latter having the pulley H, the endless apron connecting the rollers, the transverse cleats or flights K, made of angle metal, and each having one side secured to the apron and 75 the other side arranged at right angles thereto, the straps N O, connecting the inner end of the frame to the mill-case, the discharge-spout L at the outer end of the frame, and having the hopper M, and the belt connecting 80 the pulley H to the pulley on the fan-shaft, substantially as described.

In testimony that I claim the foregoing as my own I have hereto affixed my signature in presence of two witnesses.

AMBROSE DIEFFENBACH.

Witnesses:

CLINTON R. SMITH,
T. C. SAUNDERS.
